Inventor
John R. Frank
By his Attorney
Jas. S. Williamson

UNITED STATES PATENT OFFICE.

JOHN R. FRANK, OF MINNEAPOLIS, MINNESOTA.

TELEGRAPH-KEY.

SPECIFICATION forming part of Letters Patent No. 508,214, dated November 7, 1893.

Application filed May 29, 1893. Serial No. 475,817. (No model.)

To all whom it may concern:

Be it known that I, JOHN R. FRANK, a citizen of the United States, residing at Minneapolis, in the county of Hennepin and State of Minnesota, have invented certain new and useful Improvements in Automatic Switches for Telegraph-Keys; and I do hereby declare the following to be a full, clear, and exact description of the invention, such as will enable others skilled in the art to which it appertains to make and use the same.

My invention is in the nature of an improvement in telegraph keys.

As is well-known, in the present telegraph systems, there are employed, in connection with the generators and the line wire, a transmitting key and a sounder for denoting the impulses given to the current in transmitting the message. Each station is, of course, provided with both a key and a sounder; and all of the keys and all of the sounders of any given circuit are connected up in series. The key is provided with a lever and an anvil portion, insulated from each other and connected to the opposite terminals of the line. The key lever is normally spring-held away from the anvil and is depressed onto the same to close the circuit therethrough. Whenever the circuit is thus closed or opened, all the sounders along the line are operated. In order that the key may thus operate the distant sounders, it is necessary for the circuit to be continuous at all points except the break between the lever and the anvil of the particular key which is in use. Hence, there has hitherto been employed, in connection with the old style key, a hand operated switch lever, which is set to close the circuit when the key is out of use, and which is adapted to be thrown out of the circuit when the key is to be used. In the use of these keys, it frequently occurs that some operator along the line forgets to close his switch, after finishing his message. In such a case, the line will be left open, thus making it impossible to telegraph to or across the gap formed in the circuit by the opened switch. This contingency has been the cause of much loss of time, money and life. It is the object of my invention to remove this defect in the construction and use of telegraph keys.

To these ends, my invention consists in the

novel construction and arrangement of parts, the preferred form, as well as several modifications of which, are illustrated in the accompanying drawings.

Like letters refer to like parts throughout the several views.

Figure 1 is a plan view, and Fig. 2 is a vertical section taken approximately on the irregular line X X' of Fig. 1, with some parts broken away, showing a key equipped with the preferred form of my automatic switch attachment. Fig. 3 is a side elevation, illustrating a modified construction of the automatic switch device, and Fig. 4 is a transverse section taken on the line Y Y' of said Fig. 3.

a' represent the station terminals of the main line wire. b is the base, c is the lever, d the anvil, and f' are the binding or contact posts of an ordinary key, all of said parts being constructed of metal.

The lever c is fulcrumed on the metallic fulcrum block c', rising from the base b. The key lever is yieldingly held onto its fulcrum-block c' and normally out of contact with the anvil portion d, by a spring c² subject to the action of a thumb-screw c³ working through a bracket c⁴ rigid with the fulcrum-block c'. At its rear end, the lever c is provided with an adjustable thumb-screw and nut c⁵ which serves to limit its stroke. At its forward end, the lever is provided with a button or finger-piece c⁶.

The terminal wires a and a' are connected respectively, to the contact posts f and f'. Of these parts, the post f is electrically connected to the bed b and from thence through the fulcrum block c' to the key-lever c, while the post f' is insulated from the bed b, by a suitable insulating thimble f². The anvil-piece d is also insulated from the bed b by another insulating thimble d', and is electrically connected to the depending end of the contact post f', by means of a wire d², located under the bed.

The parts so far described, are in their general features, like the ordinary standard construction.

In the preferred form of my invention, the forward end of the key-lever is provided with a switch lever g, which is pivotally carried from the under side of the same, as shown at

5 *g'*. The free inner end of this switch lever *g* is normally held, by gravity or spring tension, or, as shown, by the combined action of both, in contact with a contact plate *g*², which is insulated from the bed-plate *b* and in electrical contact with the anvil piece *d*.

10 *g*⁴ is a cap-piece positioned immediately above the button or finger-piece *c*⁶, having a stem *g*⁵ passing downward and working, through an axial perforation in said button piece *c*⁶, and pivotally secured to the forward end of the switch-lever *g*, as shown at *g*⁶.

15 *g*⁷ is a light coiled spring surrounding the stem *g*⁵, working in a countersunk portion of the button *c*⁶, and tending both to keep the cap piece *g*⁴ in its uppermost position, and the switch-lever *g* in its lowermost position, in contact with the contact plate *g*².

20 The operation of this device is simple. Normally the circuit is closed from the key to the anvil, through the switch lever *g* and the contact plate *g*². In using the key, the operator by the initial operating movement, in gripping the button *c*⁶ of the key-lever *c*, depresses 25 the cap-piece *g*⁴ upon the said button, thus raising the switch-lever *g* and breaking the circuit at *g*². By thus depressing the cap-piece *g*⁴, with respect to the button *c*⁶, the free end of the switch-lever is carried away from 30 the contact plate *g*² such a distance that, in the action of depressing the key-lever onto the anvil *d*, in sending messages, the said switch-lever *g*, will not be thrown into contact with said contact-plate *g*². Hence, it 35 will be seen that this switch device can in no wise interfere with the transmitting action of the key. A very important feature in the construction of my preferred form should be here noted, to-wit:—The cap-piece *g*⁴ and the 40 upper edge of the button *c*⁶ are of the same diameter and are so supported that their peripheries are left continuous and unobstructed, and hence, when the parts are pressed together, by the operator gripping the key, the 45 peripheral edges of the parts will become, coincident, and may be gripped by the operator, at any portion of their margins. When the cap-piece *g*⁴ is depressed onto the button *c*⁶ and the two are gripped together by the operator, they are operated as an entirety, after 50

the manner of the ordinary key. Immediately upon the release of the key from the grip of the operator, the switch-lever *g* will automatically close the circuit at *g*², thus rendering all the sounders located in the circuit operative from any key along the line. 55

In the modification shown in Figs. 3 and 4, all parts are similar to those shown in Figs. 1 and 2, with the exception of the finger-piece for operating the switch-lever *g*. In this case, 60 the button *c*⁶ of the key-lever *c* is slotted and provided with a pivoted finger-piece, in the form of a bell-crank, *g*⁸, the lower end of which engages the upper edge of the forward end of the switch-lever *g*. As shown, the 65 switch-lever *g* is normally held closed by a light flat spring *g*⁹, secured to the under edge of the key-lever *c* and engaging said switch-lever with its free end. By pressing the finger-piece *g*⁸ into the button portion *c*⁶, in the 70 gripping action, the switch will be thrown out of action in a manner similar to that described in connection with my preferred form.

My device may of course, be changed in many of the details of the construction and 75 arrangement of the parts, without departing from the spirit of my invention.

The great utility of an automatic circuit closer, such as I have herein described, is obvious from the statements already made. 80

What I claim, and desire to secure by Letters Patent of the United States, is as follows:

The combination with a telegraph key, of the extended contact *g*², the self closing switch lever *g*, pivotally suspended from the key-lever at a point outward of the center of gravity of said lever *g*, the button *c*⁶ at the outer end of the key-lever, and the cap-piece *g*⁴ having the stem *g*⁵ working through said button and pivoted to the outer end of said switch-lever *g*, said button and said cap-piece having continuous coincident and unobstructed peripheral margins, substantially as and for the purpose set forth.

In testimony whereof I affix my signature in 95 presence of two witnesses.

JOHN R. FRANK.
